UNITED STATES PATENT OFFICE.

JOSEPH McMASTERS SCOTT, OF ALLEGHENY, PENNSYLVANIA.

ELECTRIC RAILWAY-SIGNAL.

SPECIFICATION forming part of Letters Patent No. 360,175, dated March 29, 1887.

Application filed April 16, 1886. Serial No. 199,083. (No model.)

To all whom it may concern:

Be it known that I, JOSEPH McMASTERS SCOTT, of Allegheny, in the county of Allegheny and State of Pennsylvania, have invented a new and Improved Electrical Block-Signal for Railroads, of which the following is a full, clear, and exact description.

The object of my invention is to provide a new and improved electrical block-signal, to which the operator cannot change without notifying the central office.

The invention consists of an electric circuit carrying the central office and the signal box, and of a signal-block, which, when moved, alternately opens and closes the main-line circuit.

The invention also consists in various parts and details and combinations of the same, as will be fully described hereinafter, and then pointed out in the claim.

Reference is to be had to the accompanying drawings, forming a part of this specification, in which similar letters of reference indicate corresponding parts in all the figures.

Figure 1 is a side elevation of my improvement. Fig. 2 is an end elevation of the same. Figs. 3 and 4 represent modifications hereinafter more fully described. Fig. 5 is an enlarged front elevation of the spring-bar and the notched disk.

Each of the signal-boxes, A A', &c., is attached to a post, B, is constructed in any suitable manner, and is provided with the stationary signal-block C and the lamp D, for use at night. On an arm, E, secured to either the inside or outside of the box A, is mounted at each side a shaft, F, on each of which shafts is fastened a red signal-block, G, a notched disk or wheel, H, and a crank-arm, I, on which is fastened the rod J, extending downward.

A spring-bar, K, is secured at its inner end to the arm E, and is provided with a lug, L, which engages with the periphery of the notched disk H. The free inner end of the bar K can connect with the central fixed plate, M, fastened to the arm E. The outer end of the bar K of the first signal-box, A, in the line connects by a wire, N, with an ordinary Morse

instrument, an indicator, or an annunciator situated at the central station or office, O. 50

The different signal-boxes in the line are connected with each other by the wire P, and the last signal-box in the line connects, by means of the wire Q, with the ground, thus establishing a complete circuit with the main office O. 55

The operation is as follows: If the operator at any of the signal-boxes throws the red signal-block G upward by pulling on the rod J, attached to the crank-arm I, secured on one of the shafts F, it causes said signal-block G to swing outward, and as the notched disk H turns with the shaft F it alternately connects and disconnects the lug L of the spring-lever K with the central plate, M, whereby the main-line circuit is alternately opened and closed, and this is indicated by the respective instrument in the central office O. In case the operator moves the signal-block wrongly, the central office is notified of this fact at once 70 and can communicate in any suitable manner with the operator, who can correct his mistake. The notches in one of the disks on a signal-box may be so arranged that when said disk H makes one-quarter revolution it telegraphs, for instance, according to the Morse key, "S. B. West," as shown in Fig. 5, while the notches on the other disk of the same box indicate "S. B. East"—that is, "signal-block standing east." 75

Instead of having a signal-block swinging on the shaft, it may also be constructed as shown in Fig. 3, in which the signal-block is suspended by a rope, R, passing over a pulley, and is provided on one edge with notches 85 which engage the lug on the spring-bar K when the signal-block slides upward. In Fig. 4 the arrangement is similar, but the notched strip is attached directly to the wire or rope. 8c

Having thus fully described my invention, I claim as new and desire to secure by Letters Patent—

In an electric railway signaling system, a closed circuit including a number of signaling devices and a recording device located at a 95 station, which signaling devices comprise a

visual signal having thereon a series of irregularly-arranged notches and adapted to be operated by hand, and a contact-point engaging with said notches, which visual signal, as it is operated or manipulated, effects the movement of said notches past said contact-point, whereby when a signal is set or displayed the

fact is recorded at the station by means of the several impulses sent over the line, substantially as and for the purpose set forth.

JOSEPH McMASTERS SCOTT.
